"Pot Holder Apron".*Primary Examiner—C. A. Murphy
Attorney, Agent, or Firm—Frijouf, Rust & Pyle***[57] CLAIM**

The ornamental design for an apron, as shown and described.

DESCRIPTION

FIG. 1 is a perspective view of an apron showing my new design;

FIG. 2 is a reduced front elevational view thereof, the waist band being shown broken away for ease of illustration;

FIG. 3 is a rear elevational view of FIG. 2;

FIG. 4 is an enlarged left side view thereof;

FIG. 5 is an enlarged right side view thereof;

FIG. 6 is an enlarged top plan view of FIG. 2;

FIG. 7 is an enlarged bottom plan view of FIG. 2;

FIG. 8 is a front elevational view of FIG. 2, the broken lines showing attached personal articles being for illustrative purposes only and forming no part of the claimed design;

FIG. 9 is a front elevational view of an alternate embodiment of the design shown in FIG. 1, the waist band being shown broken away for ease of illustration;

FIG. 10 is a rear elevational view of FIG. 9;

FIG. 11 is a left side elevational view of FIG. 9;

FIG. 12 is a right side elevational view of FIG. 9;

FIG. 13 is a top plan view of FIG. 9; and,

FIG. 14 is a bottom plan view of FIG. 9.

The broken lines shown in the claimed article in FIGS. 1 through 3 and FIGS. 8 through 10 are understood to represent conventional stitching.
